UNITED STATES PATENT OFFICE.

DAVID F. CURTIN, OF CHICAGO, ILLINOIS.

SANITARY PAPER CUP AND DISH.

1,188,046.

Specification of Letters Patent. Patented June 20, 1916.

Application filed January 27, 1914, Serial No. 814,679. Renewed November 11, 1915. Serial No. 60,994.

To all whom it may concern:

Be it known that I, DAVID F. CURTIN, a citizen of the United States, and a resident of Chicago, in the county of Cook and State 5 of Illinois, have made certain new and useful Improvements in Sanitary Paper Cups and Dishes, of which the following is a specification.

My invention is an improvement in sanitary paper cups and dishes, and has for its 10 object to provide a cup or dish formed from a blank cut to shape and creased, and afterward folded in a particular manner to form a receptacle for containing soda fountain 15 products, and especially adapted for use in the soda cup holders and dishes forming the subject matter of my co-pending applications, Serial No. 799,705 and Serial No. 805,035.

20 In the drawings: Figure 1 is a perspective view of a form of cup, Fig. 2 is a plan view of the blank from which the cup shown in Fig. 1 is formed, Fig. 3 is a partial horizontal section of the holder forming the subject matter of my above-mentioned co-pending patent, showing the manner of holding the formed dish in position to hold ice cream or the like, Fig. 4 is a perspective view of a soda cup, and 25 Fig. 5 is a plan view of the blank from which the cup shown in Fig. 4 is formed.

The embodiment of the invention shown in Figs. 1 to 3 inclusive is formed from a paper blank 1 of approximately circular 30 form but having a strip indicated at 2 removed from the blank at the periphery thereof. The said strip 2 is bounded between two radii at an angle of 90 degrees with respect to each other, the periphery 35 of the blank, and an arc parallel with the periphery. Crease lines 3 are then formed in the blank leading from the center 4 thereof to the radial shoulders 5 which are formed by the removal of the strip 2 before 40 mentioned. The said lines 3 are radius lines, and coincide with the shoulders 5 before mentioned. A third crease line 6 is formed leading from the center 4 of the blank to a point halfway between the shoulders 5, that is halfway between the radius 45 lines 3.

The dish is formed by bending the blank on the crease lines 3 and 6, that portion of the blank between the radius lines 3 being bent outward, and doubled upon 50 itself, upon the radius lines 6. The radius

line 6 is halfway between the radius lines 3, so that the portions 7 between each radius line 3 and the radius line 6 are of equal size. A flap shown in Figs. 1 and 3 is thus 60 formed by the two portions 7, extending radially with respect to the dish, the remaining portion of the blank constituting a conical cup or dish, as shown.

The holder 8 forming the subject matter 65 of the above-mentioned application No. 805,035 has a slot extending from the center thereof to near the rim, and the opposite sides of the slot are offset with respect to each other, as indicated at 9 and 10 in Fig. 3. The flap formed by the folding of the portions 7 upon each other is passed through the slot, and the sides 9 and 10 of the slot clamp upon the flap, to hold it 70 in place, and to prevent leakage at this 75 point.

The rim of the holder is beaded over, and the free edge of the blank 1 is bent over the said bead, as shown at 11 in Fig. 1, 80 to cover the bead.

After the dish or cup has been used, it may be withdrawn from the holder and destroyed, a cup or dish being provided for each purchaser and each cup or dish is used but once. The paper from which the cups 85 and dishes are formed may be of any desired material, as for instance plain paper, paraffin paper, or paper otherwise prepared for use.

The embodiment of the invention shown 90 in Figs. 4 and 5 is more especially designed for use with the soda cup holder forming the subject matter of my above-mentioned co-pending application, Serial No. 799,705. The said cup is formed from a single blank 95 12 of approximately segmental shape, having two straight sides and one arc-shaped or curved side. The said blank may be considered as being originally of semi-circular shape, and having one end cut off.

That portion of the cup between the line 13 and the base or diameter line of the blank indicated at 15 is then formed into conical shape, as shown in Fig. 4, with that portion between the line 13 and the short 105 defining straight line 16 forms a flap engaging the outer face of the opposite end of the blank, and being sealed thereto to form the conical receptacle shown in Fig. 4.

The improved cups may be shaped and 110 furnished in nested form. The holders forming the subject matter of the above-

mentioned application have each a conical receiver for the cup, and each receiver has an opening at its apex through which the apex of the paper cup or dish extends.

- 5 After the cups or dishes have been used, they may be easily removed from the holders, merely by pressing upward on the protruding apices.

The arrangement of the flap formed by 10 the portions 7 of the construction of Figs. 1 and 2, provides a lock for preventing accidental removal of the dish from the holder. The lock will hold the dish in place under ordinary circumstances, but will not 15 interfere with the speedy removal of the same when desired.

I claim:

1. A cup or dish of the character specified, formed from a blank of approximately 20 circular form, said blank being creased from the center to the periphery on two lines at an angle of 90° with respect to each other, and having a strip removed at the periphery between the two lines and an arc parallel 25 with the periphery, and having a third crease from the center of the strip to the center of the blank, that portion of the blank between the first-named crease lines being folded outwardly and doubled upon

itself to form a conical receptacle and a 30 radial flap, the free edge of the blank being bent outwardly in beaded form.

2. A cup or dish of the character specified, formed from a blank of approximately circular form, said blank being creased from 35 the center to the periphery on two lines at a substantial angle with respect to each other, and having a strip removed at the periphery between the two lines and an arc parallel with the periphery, and having a 40 third crease from the center of the strip to the center of the blank, that portion of the blank between the first-named crease lines being folded outwardly and doubled upon 45 itself to form a conical receptacle and a radial flap.

3. A cup or dish of the character specified, formed from a blank of approximately circular form, said blank being creased from the center to the periphery on two lines at 50 a substantial angle with respect to each other, and having a strip removed at the periphery between the two lines, and an arc parallel with the periphery.

DAVID F. CURTIN.
